(57) **CLAIM**

The ornamental design for an intranasal therapy delivery system, as shown and described.

DESCRIPTION

FIG. 1 is a perspective view of an intranasal therapy delivery system showing my new design with the cap removed;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a perspective view of the intranasal therapy delivery system with the cap installed;

FIG. 8 is a front view thereof;

FIG. 9 is a back view thereof;

FIG. 10 is a right side view thereof;

FIG. 11 is a left side view thereof; and,

FIG. 12 is a top view thereof.

The broken lines around the circumference of the neck or upper portion of the irrigator in FIGS. 1-5 and 7-11 which define the bounds of the claimed design form no part thereof. The broken line showing of a power jack cover at the bottom of FIGS. 1, 2, 4-8 and 10-12 and the broken line showing of a release button, alignment indicator, switch, and battery icon at the top of FIGS. 3 and 10 are all for the purpose of illustrating portions of the article and form no part of the claimed design. Bottom views are omitted as they are flat and devoid of surface ornamentation.
